BUNK FEEDER

Furman E. Ott, Rte. 3, Laurens, S.C. 29360

Filed Mar. 13, 1967, Ser. No. 6,199

Term of patent 14 years

(Cl. D30—13)

Fig. 1.

Fig. 2.

FIGURE 1 is a front perspective view of the bunk feeder, and

FIGURE 2 is a perspective view of the bunk feeder taken from the rear of FIGURE 1 further illustrating my new design.

I claim:

The ornamental design for a bunk feeder, substantially as shown.
